UNITED STATES PATENT OFFICE

GORDON FOX, OF CHICAGO, ILLINOIS, ASSIGNOR TO FREYN ENGINEERING COMPANY, OF CHICAGO, ILLINOIS, A CORPORATION OF MAINE

ELECTRIC BELL HOIST

Application filed November 28, 1928. Serial No. 322,334.

The present invention relates to electric bell hoists.

More particularly the present invention relates to systems for manipulating the bells of a blast furnace charging system. Blast furnaces are commonly provided with one or more charging bells at their upper extremities, which bells, between charging operations, are held in closed positions. When 10 said bells are in said closed positions, material may be deposited thereon. The present invention contemplates electric control means applicable to charging bells such as referred to.

An object of the present invention is to provide operating means for a bell hoist which will cause the effectual sealing of the bell in closed position between dumping operations and which will cause said bell to 20 open and close in a safe manner.

A further object is to provide a bell hoist utilizing relatively simple instrumentalities, which bell hoist will effectually hold the bell in closed position between dumping 25 operations and which will prevent the bell from attaining dangerous speeds while in motion.

A further object is to provide an improved bell hoist well adapted to meet the 30 needs of commercial operation.

Further objects will appear as the description proceeds.

Referring to the drawings—

Figure 1 is a more or less schematic view 35 illustrating a layout embodying the principles of the present invention;

Figure 2 is a plan view including motive means forming part of the layout illustrated in Figure 1;

Figure 3 shows, on an enlarged scale, part 40 of the structure shown in Figure 2;

Figure 4 is a view in side elevation, parts being broken away, of the structure shown in Figure 3;

Figure 5 shows a detail of construction;

Figure 6 is an end view of the structure shown in Figure 3, part being broken away to show the connection between the winding drum and its associated gear;

Figure 7 is a schematic view illustrating the arrangement of certain limit switches employed in the illustrated embodiment of the present invention; and

Figure 8 is a diagrammatic view of an electric circuit forming part of the present invention.

Referring first to Figure 1, the reference character A indicates one bell and the character B indicates a second and larger bell, which cooperate with one another in the loading of the blast furnace C. The two bells A and B may be arranged co-axially in a manner which is common practice, the bell A being controlled by a cable D, while the larger bell B is controlled by a cable E; levers F and G being connected to said cables D and E, respectively, and being also connected to the bells A and B, respectively.

The cable D is connected to the winding drum of an electric hoisting mechanism, indicated as a whole by the reference character H, and the cable E is connected to the winding drum of a hoisting mechanism indicated as a whole by the reference character J. The hoisting mechanisms H and J 70 may be similar in their principles of operation, and a description of one of said hoisting mechanisms will suffice for both.

Referring now more particularly to Figures 3, 4 and 5, hoisting mechanism is illustrated which may be used for either hoisting mechanism H or hoisting mechanism J. The hoisting mechanism illustrated in these figures includes the cable drum 1, which drum is keyed to the shaft 2 and has secured thereto the gear 3. Said shaft 2 is rotatably carried by bearings 4—4 forming part of structural supports 5—5 spaced apart a sufficient distance to swingingly support certain operating mechanism, which for purposes of con- 85

venience in this specification will be termed a tailpiece, and which will be indicated as a whole by the numeral 6. The shaft 2 is provided intermediate of the bearings 4-4 with journal portions 7-7 for carrying bearings 8-8 for swingingly supporting the tailpiece 6. Said bearings 8-8 are secured to arms 9-9, which arms may be provided adjacent to their outer swinging extremities with the counterweight 10. At their outer extremities, the arms 9-9 are provided with the cross connector 11, provided with spring bumpers 12-12 adapted to yieldably contact with rigid abutments 13-13 (see Figure 1).
15 At a region adjacent to the counterweight 10, the arms 9-9 support an electric motor 14, which motor is geared to the gear 3 through a train of gears as follows: The rotor of said motor 14 is provided with the pinion 15, which meshes with the gear 16. Said gear 16 is secured to a shaft 17 having bearings in the two arms 9-9. Secured to the shaft 17 is the pinion 18 meshing with the gear 19. The gear 19 is secured to the shaft 20, which is rotatably carried in bearings supported by the arms 9-9. The shaft 20 has secured thereto the pinion 21, which meshes with the gear 22. Said gear 22 is secured to the shaft 23 supported in bearings 25 carried by the arms 9-9. Secured to said shaft 23 is the pinion 24 meshing with the gear 3. It will be understood without detailed explanation that when the motor 14 operates with motoring functions it will, through the train of gears immediately above described, communicate a relatively slow turning movement to the gear 3 and consequently to the winding drum 1. It will also be understood that when the winding drum 1 is positively rotated by the cable D or E associated with it, motion will be communicated to the rotor of said motor 14.

Secured to the cross member 11 is a chain 25, said chain being connected to said cross member 11 by means of the tension spring 26. The other extremity of said chain 25 may be secured to a relatively fixed abutment (not shown). Said chain 25 will have the function of limiting the swinging movement of the tailpiece 6 in a counterclockwise direction as the parts are viewed in Figure 4.

Secured to the rotor of the motor 14 is a brake mechanism indicated as a whole by the numeral 27. The brake mechanism need not be described in detail, inasmuch as mechanism suitable for the purpose is well known to those skilled in the art and may be readily purchased in the open market. It may be stated briefly that said brake mechanism should be biased to braking relationship with the rotor of the motor 14 and that said brake may be released by the application of electric power thereto.

65 By reference to Figure 4 it will be noted

that the shaft 17 is provided with a sprocket gear 28, which, through the medium of a sprocket chain 29, drives a sprocket gear 30 connected to a screw shaft 31. By reference to Figure 7 it will be noted that the screw shaft 31 is provided with the nut 32, which may be non-rotatably held, whereby as said screw shaft 31 is turned said nut will be caused to take a motion of translation along said screw shaft. Said nut 32, as it travels from its right-hand limit to its left-hand limit, as shown in Figure 7, successively operates limit switches 33, 34 and 35. On the return trip, that is—from its left-hand limit to its right-hand limit as shown in Figure 7, said nut successively operates limit switches 36 and 37. Said switch 33 is normally closed, limit switch 34 is normally closed, limit switch 35 is normally open, limit switch 36 is normally closed, and limit switch 37 is normally closed.

Before proceeding with a description of the electric circuits shown in Figure 8, a brief outline of a cycle of operation of the structure described up to this point will be given. Referring for purposes of this description to the large bell B, let it be assumed that said bell B is in open position, the burden which had been loaded upon said bell having been discharged into the blast furnace C. The next step is to close said bell B. In order to accomplish the closing of said bell, the brake mechanism 27 will be released and current will be applied to the motor 14 to energize same to communicate a movement of rotation to the pinion 15 of the hoisting mechanism J. Inasmuch as said pinion 15 is geared to the winding drum 1, said winding drum will be caused to rotate in a direction to reel up the cable E carried by said drum. The winding up of the cable E will communicate a clockwise movement to the lever G, and the bell B will be raised and thereby closed. When the bell B is fully closed and against its seat, the motor 14 is still allowed to rotate the drum 1. Since no more cable can be wound up, the tailpiece 6, together with the motor 14, the counterweight 10 and the gears connecting the motor 14 to the drum 1, will be raised, rotating on the shaft 2. After said tailpiece 6 has been tilted a predetermined amount, the sprocket chain 29 will have communicated sufficient turning movement to the screw shaft 31 to cause the interruption of power supply to the motor 14 and to the brake mechanism 27. The motor 14 will be stopped and the brake mechanism 27 will be set, holding the tailpiece 6 in its elevated position. Thus the weight of the motor 14, the counterweight 10, the framework of the tailpiece 6 and the gears connecting the motor 14 to the drum 1 will be applied to keep the bell B against its seat. When it is desired to open the bell B, a

120

125

130

push button, or similar mechanism, is operated to apply electric power to the brake mechanism 27, releasing said brake from the shaft of the rotor of the motor 14. Power is also applied to the motor 14, whereby the tailpiece 6 will be retarded in its descent from its elevated position. Expressed in other language, power will be applied to the motor 14 at the time that the braking mechanism 27 is released, whereby said motor will operate with generating functions to provide a dynamic braking effect to retard the speed of descent of the tailpiece 6. Said tailpiece 6 will descend slowly and will land with the spring bumpers 12-12 upon their abutments. The weight of the bell B together with its burden causes the drum 1 to revolve while the bell B is descending into the furnace. The pull upon the cable E caused by the descent of the bell B communicates a turning movement to the drum 1 and gear 3, which turning movement is communicated to the rotor of the motor 14. Electric power is still applied to said motor 14, whereby the dynamic braking effect is still maintained. Incident to the rotation of the drum 1 and gear 3 is rotation of the shaft 17, which, through the sprocket chain 29, continues to rotate the screw shaft 31. When the bell B has reached a point of sufficient opening, limit switch 34 is caused to open, interrupting the power supplied to the motor 14 and brake mechanism 27, whereby the motor is open-circuited and the brake mechanism 27 is set. After a predetermined delay, the motor 14 is again put in motion through the instrumentality of a time delay relay or equivalent mechanism, the bell B is caused to close, and the tailpiece 6 is elevated, thereby completing the cycle. As indicated above, the bell A may be controlled by similar mechanism.

The electric circuits for accomplishing the cycle above recited will now be described. The numerals 38-38 indicate the two sides of an electric circuit. Connected across the the mains 38-38 is a circuit including the switch contacts 39-39, normally open contactor 40, armature 41 of the motor 14, series field winding 42 of said motor 14, operating coil 43 of the brake mechanism 27, normally open contactor 44, normally open contactor 45 and normally open contactor 46. Bridged across the normally open contactor 44 is the resistance 47, and bridged across the normally open contactor 45 is the resistance 48. Bridged across the normally open contactor 40 and armature 41 is a circuit including the normally open contactor 49 and the resistances 50 and 51. Bridged across the resistance 51 is the normally open contactor 52. Bridged across the circuit of the armature 41 and the series field winding 42 is a circuit including the resistance 53 and the normally closed contactor 54.

Bridged across the circuit of the brake coil 43, normally open contactor 44 and normally open contactor 45 is a circuit including the normally closed contactor 54 and the normally open contactor 55.

Also connected across the mains 38-38 is a circuit including the start button 56, the operating coil 57 of contactor 49, the normally closed contactor 58 and the normally closed limit switch 34. Contact 58 is an auxiliary contact on contactor 40. Contact 58 is closed when contactor 40 is open and is open when contactor 40 is closed. Bridged across the start button 56 is the normally open contactor 59. Said contactor 59 is an auxiliary contactor connected to operate with contactor 46. Said contactor 59 is open when contactor 46 is open and is closed when contactor 46 is closed. Bridged across the operating coil 57 of contactor 49 is the operating coil 60 for controlling contactor 55. Bridged across the circuit of start button 56 and operating coil 57 is a circuit including coil 61 for controlling contactor 46 and the normally open contactor 62. Said contactor 62 is an auxiliary contactor on contactor 49 and is open when contactor 49 is open and closed when contactor 49 is closed. Bridged across the coil 61 of contactor 46 is the operating coil 63 for controlling contactor 54. Said coil 63 may be connected across the mains 38-38 not only through the normally open contactor 62, normally closed contactor 58 and normally closed limit switch 54, but also through the normally open contactor 64, normally closed contactor 65 and normally closed limit switch 37, which normally open contactor 64 is an auxiliary contactor connected to move with contactor 40, being open when contactor 40 is open and closed when contactor 40 is closed. Contact 65 is an auxiliary contactor connected to operate with contactor 49, being closed when contactor 49 is open and open when contactor 49 is closed. Bridged across the circuit of operating coil 57, normally closed contactor 58 and limit switch 34 is the operating coil 66 for contactor 52, the normally open contactor 67, the normally open contactor 68 and the normally closed limit switch 33. Said normally open contactor 67 is an auxiliary contactor connected to move with contactor 49, being open when contactor 49 is open and closed when contactor 49 is closed. Contact 68 is an auxiliary contactor connected to move with contactor 55, being open when contactor 55 is open and closed when contactor 55 is closed. Bridged across the circuit of coil 66 and normally open contactor 67 is the operating coil 69 for controlling the normally open contactor 45. Also bridged across said coil 66 and normally open contactor 67 is a circuit including the operating coil 70 for contactor 44 and the normally open con-

tactor 71. Said contactor 71 is an auxiliary contactor connected to move with contactor 45, being open when contactor 45 is open and closed when contactor 45 is closed.

5 It will be noted that the three circuits immediately above mentioned, to wit—the circuits of coil 66 with contactor 67, coil 69 and coil 70 with contactor 71 are parallel with one another. Circuit across the mains 10 38—38 through the start button 56 and said three parallel circuits is adapted to be completed through the normally closed contactor 72 and limit switch 36. Said contactor 72 is an auxiliary contactor connected to move 15 with contactor 55. Said contactor 72 is closed when contactor 55 is open and is open when contactor 55 is closed.

Also connected across the mains 38—38 20 is a circuit including the operating coil 73 of a time delay relay, indicated by the numeral 74, (to be referred to presently), and the normally open limit switch 35.

Also connected across the mains 38—38 is 25 a circuit including the normally open contactor 75 of the time delay relay 74, operating coil 76 of contactor 40, normally closed contactor 65 and normally closed limit switch 37. Bridged across the contactor 75 of the time delay relay 74 is the normally 30 open contactor 77. Said contactor 77 is an auxiliary contactor on contactor 40, being open when contactor 40 is open and closed when contactor 40 is closed.

35 A typical cycle of operation of the electrical instrumentalities above described corresponding to the cycle of the mechanical instrumentalities hereinabove described is substantially as follows: In describing the cycle of the mechanical elements a start 40 is made at the time when the large bell B is in open position, the burden having been discharged into the blast furnace. Under these conditions the nut 32 (Figure 7) will be at the left-hand limit of its travel 45 as the parts are viewed in Figure 7, under which conditions limit switch 34 will be open and limit switch 35 will be closed. Inasmuch as limit switch 35 is closed, the operating coil 73 of the time delay relay 74 is 50 energized, resulting in the closure of contactor 75 of said time delay relay 74. Closure of the contactor 75 completes a circuit from the left-hand main 38 through the operating coil 76 of contactor 40, the normally 55 closed contactor 65 and the normally closed limit switch 37, to the right-hand main 38. Energization of operating coil 76 results in the closure of the normally open contactor 40 as well as the auxiliary contactor 77 connected to move in unison with said contactor 40. Closure of auxiliary contactor 77 bridges the contactor 75 of the time delay relay 74, maintaining circuit through the operating coil 76 after the nut 32 has moved 65 toward the right as the parts are viewed in

Figure 7. Inasmuch as the auxiliary contactor 64 moves in unison with contactor 40, the closure of said contactor 40 is accompanied by the closure of contactor 64, completing a circuit from the left-hand main 70 38 through the operating coil 63 of contactor 54, contactor 64, normally closed contactor 65 and normally closed limit switch 37 to the right-hand main 38. Energization of coil 63 results in the opening of normally 75 closed contactor 54. Inasmuch as operating coil 61 (controlling contactor 46) is in parallel with coil 63, said coil 61 is also energized, resulting in the closing of normally open contactor 46. Closure of contactors 40 and 46 completes a circuit from the left-hand main 80 38 through contactor 40, armature 41, series field winding 42, operating coil 43 of the brake mechanism 27, resistances 47 and 48 and contactor 46 to the right-hand main 85 38. Due to the energization of the operating coil 43, the brake mechanism 27 will be released, and due to the energization of the armature 41 and the series field winding 42, the motor 14 will be set in operation. 90

As said motor, including the armature 41 and field winding 42, starts up, resistances 47 and 48 will be automatically cut out of circuit, through automatic switching means, which need not be described herein, such means being well known to those skilled in the art. Operation of the motor will cause movement of the nut 32 toward the right from its left-hand limit of travel as the parts are viewed in Figure 7, allowing normally closed limit switch 34 to close and normally open limit switch 35 to open. Opening of limit switch 35 has no effect upon the energization of the operating coil 76 of contactor 40, inasmuch as the contactor 75 of the time delay relay 74 is bridged by the contactor 77, which is closed when contactor 40 is closed. It will be noted that contactor 65 and limit switch 37 are closed at this time. 100

The motor 14, comprising the armature 41 and series field winding 42, continues to raise the bell. At the time or shortly before the bell is seated, the nut 32 causes the opening of the normally closed limit switch 36. The opening of the limit switch 36 results in the deenergization of the operating coils 69 and 70, resulting in the opening of contactors 45 and 44, respectively, reinserting resistances 47 and 48 in circuit with the armature 41 and series field winding 42, resulting in the slowing down of the motor 14 (which includes the armature 41 and series field winding 42). The slowing down of the motor 14 prevents the violent closure of the bell B and produces the result that the tail-piece 6 will be raised slowly. As mentioned above in the description of the cycle of operation of the mechanical instrumentalities, the motor 14 will continue to operate after 110 115 120 125 130

the bell B is closed, such continued operation resulting in the raising of the tailpiece 6, insuring the sealing of the bell B to its seat. When the tailpiece 6 has been raised a predetermined amount, the nut 32 will be at the right-hand limit of its travel, resulting in the opening of the normally closed limit switch 37. Opening of the limit switch 37 results in the deenergization of operating coil 76, allowing contactors 40 and 46 to open, thereby deenergizing the operating coil 43 of the brake mechanism 27 and setting the brake, whereby the bell B is held closed and the tailpiece 6 is held in elevated position.

The material may now be deposited upon the bell B for the next succeeding dumping operation. When the bell B has been loaded, the start button 56 may be closed, either manually or automatically, in response to any predetermined function. Closure of start button 56 results in the energization of operating coils 57 and 60, which coils cause the closure of normally open contactor 49 and normally open contactor 55. Closure of contactor 49 results in the closure of the auxiliary contactor 62, whereby operating coil 61 of contactor 46 is energized. Energization of coil 61 results in the closure of contactor 46. Inasmuch as operating coil 63 of normally closed contactor 54 is in parallel with coil 61, the closure of start button 56 will cause the opening of said normally closed contactor 54. Closure of start button 56 will also result in the energization of operating coils 66, 69 and 70, which coils are in parallel circuits. It will be noted that contactor 67 is closed by reason of the fact that contactor 49 is closed; also that contactor 68 is closed by reason of the fact that contactor 55 has been closed. Limit switch 33 is closed at this time. Inasmuch as operating coil 69 of contactor 45 is bridged across the operating coil 66 and the contactor 67, said operating coil 69 will be energized at this time, resulting in the closure of normally open contactor 45. Inasmuch as normally open contactor 71 closes with contactor 45, operating coil 70 will be energized at this time, resulting in the closure of the normally open contactor 44.

A circuit is now complete from the left-hand main 38 through contactor 49, resistance 50, contactor 52, series field winding 42, brake operating coil 43 and contactors 44, 45 and 46, to the right-hand main 38. A dynamic braking circuit is also completed from the left-hand brush of the armature 41 through the resistance 53, contactors 55, 45 and 44, brake operating coil 43, series field winding 42, to the right-hand brush of armature 41. Inasmuch as the brake operating coil 43 is deenergized, the brake mechanism 27 is released at this time, allowing the tailpiece 6 to descend. Excessive speed of de-

scent of the tailpiece 6 is prevented by reason of the dynamic braking effect of the current set up in the braking circuit immediately above referred to. After the tailpiece 6 has descended to its foundations, the weight of the bell B together with its burden will cause the drum 1 to revolve, communicating further rotation to the rotor of the motor 14. Inasmuch as the weight of the tailpiece 6 is no longer effective at this time to cause rotation of the rotor of the motor 14, it is desirable to decrease the dynamic braking effect of the motor 14. According to the illustrated embodiment of the present invention, this decrease in the dynamic braking effect of the motor 14 is accomplished by the limit switch 33. Rotation of the rotor of the motor 14 will cause the nut 32 to travel to the left as the parts are viewed in Figure 7, opening the normally closed limit switch 33, interrupting the circuit of the operating coils 66, 69 and 70, resulting in the opening of contactors 52, 45 and 44, respectively, inserting resistances 51, 48 and 47. Inasmuch as the dynamic braking effect of the motor 14 is decreased by the insertion of said resistances 51, 48 and 47, the bell with its burden will be allowed to descend at a practicable speed, until the nut 32 has reached the left-hand limit of its travel as the parts are viewed in Figure 7, resulting in the opening of the normally closed limit switch 34 and the closure of the normally open limit switch 35. Opening of limit switch 34 results in the deenergization of operating coils 57, 60, 61 and 63, resulting in the opening of contactors 49, 55 and 46 and the closure of contactor 54. Closure of contactor 54 completes a dynamic braking circuit across the armature 41 through the resistance 53, contactor 54 and series field winding 42, insuring an effective dynamic braking of the motor 14. This insures safety of action in case any failure should occur in the brake mechanism 27 controlled by the brake operating coil 43. It will be noted that inasmuch as contactor 46 has been opened, the brake operating coil 43 is deenergized and the brake mechanism 27 is set. This completes the cycle referred to.

The present invention, it will be noted, utilizes only relatively simple instrumentalities, most of which are readily purchasable in the open market. Space and material are minimized, inasmuch as the motor acts as part of the counterweight for holding the bell in closed position, which motor and associated parts operate with a leverage action, whereby the sealing effect is decidedly efficient. Though the disclosure includes a counterweight, said counterweight need be only relatively small compared to those used in other systems with which applicant is familiar.

As indicated above, each of the bells of a

blast furnace may be provided with a hoisting and control system such as has been described above.

Though a preferred embodiment of the present invention has been described in detail, many modifications will occur to those skilled in the art. It is intended to cover all such modifications that fall within the scope of the appended claims.

What is claimed is—

10. 1. In combination, a weighted movable member, stop means for limiting upward movement of said member, an operating cable for lifting said member, a winding drum for said cable, and motive means connected to said drum, said motive means being tiltably mounted for movement about the axis of said drum, whereby after said motive means has raised said weighted member up against said stop means continued operation of said motive means will cause the tilting of said motive means.
15. 2. In combination, a weighted movable member, a drum connected to said weighted member, a dynamo-electric machine spaced from but connected in driving relationship to said drum, said dynamo-electric machine being tiltably mounted about the axis of rotation of said drum, and stop means for limiting the travel of said weighted member at the upper limit of its range of movement, whereby continued operation of said dynamo-electric machine with motoring functions after said weighted member has 20 reached said limit will result in the elevation of said dynamo-electric machine.
25. 3. In a bell hoist, in combination, a charging bell, a seat for said bell limiting the upward movement of said bell, cable means for said bell, a winding drum for said cable means, an electric motor operatively connected to said winding drum, and means tilttable about the axis of said drum, said motor being carried by said tilttable means 30 at a region spaced from the axis of rotation of said drum.
35. 4. In combination, a weighted movable member, a drum operatively connected to said weighted member for lifting said weighted member under certain predetermined conditions and for operation by said weighted member under certain other predetermined conditions, a tilttable member mounted for swinging movement about the axis of said drum, and a dynamo-electric machine carried by said tilttable member, said dynamo-electric machine being cooperatively connected to said drum whereby said dynamo-electric machine is capable of 40 tilting said tilttable member when said weighted member has been lifted to the limit of its upward travel.
45. 5. In combination, a weighted movable member, a rotatable member operatively connected to said weighted member for lift-

ing said weighted member under certain predetermined conditions and for operation by said weighted member under certain other predetermined conditions, a tilttable member mounted for swinging movement about the axis of said rotatable member, a dynamo-electric machine carried by said tilttable member, said dynamo-electric machine being cooperatively connected to said rotatable member whereby said dynamo-electric machine is capable of tilting said tilttable member when said weighted member has been lifted to the limit of its upward travel, said dynamo-electric machine being provided with dynamic braking circuit means, and limit switch means for selectively controlling said dynamic braking circuit means at different values during the descent of said tilttable member from tilted position and during the operation of said rotatable member under the influence of said weighted member.

6. In combination, a weighter movable member, a drum operatively connected to said weighter member for lifting said weighter member under predetermined conditions and for operation by said weighter member under other predetermined conditions, mounting means, a dynamo-electric machine secured to said mounting means, a base for said mounting means, said dynamo-electric machine and said mounting means being capable of upward movement from said base when said weighter member is held in fixed position, said dynamo-electric machine being cooperatively connected to said drum whereby said dynamo-electric machine is capable of lifting said mounting means when said weighter member has been lifted to its limit of upward travel, said dynamo-electric machine being provided with dynamic breaking circuit means and limit switch means for controlling the dynamic breaking effect of said dynamo-electric machine during the descent of said mounting means from elevated position.

7. In combination, a weighted movable member, a rotatable member operatively connected to said weighted member for lifting said weighted member under predetermined conditions and for operation by said weighted member under other predetermined conditions, mounting means, a dynamo-electric machine secured to said mounting means, said dynamo-electric machine and said mounting means being capable of upward movement when said weighter member is held in fixed position, said dynamo-electric machine being cooperatively connected to said rotatable member whereby said dynamo-electric machine is capable of lifting said mounting means when said weighter member has been lifted to its limit of upward travel, said dynamo-electric machine being provided with dynamic

braking circuit means and limit switch means for selectively controlling said dynamic braking circuit means at different values during the descent of said mounting means from elevated position and during the 5 operation of said rotatable member under the influence of said weighted member.

Signed at Chicago, Illinois, this 23rd day of November, 1928.

GORDON FOX.
